US00D907864S

(12) **United States Design Patent** (10) Patent No.: **US D907,864 S**
(45) Date of Patent: **** Jan. 12, 2021**

(54) **CHICKEN FEEDER**

(71) Applicant: **Lyle Mead Schwartz**, Flagstaff, AZ (US)

(72) Inventor: **Lyle Mead Schwartz**, Flagstaff, AZ (US)

(**) Term: **15 Years**

(21) Appl. No.: **29/689,450**

(22) Filed: **Apr. 30, 2019**

(51) LOC (13) Cl. **30-03**

(52) U.S. Cl.

USPC **D30/131; D30/121**

(58) **Field of Classification Search**

(57) **CLAIM**

The ornamental design for a chicken feeder, as shown and described.

DESCRIPTION

FIG. 1 is a perspective view of a chicken feeder; FIG. 2 is a right side elevation view thereof; FIG. 3 is a left side elevation view thereof; FIG. 4 is a front elevation view thereof; FIG. 5 is a rear elevation view thereof; FIG. 6 is a top plan view thereof; and, FIG. 7 is a bottom plan view thereof.

The broken lines shown in the drawings depict portions of the chicken feeder that form no part of the claimed invention.

1 Claim, 6 Drawing Sheets
